LEO J. GRUBMAN, OF BELLE HARBOR, LONG ISLAND, NEW YORK, ASSIGNOR TO MARGON CORPORATION, OF NEW YORK, N. Y., A CORPORATION OF NEW YORK

EYE MOUNTING FOR DOLLS

Application filed January 18, 1927. Serial No. 161,725.

This invention relates to eye mountings for dolls and attaching tools therefor, and has for its primary object to provide improved means for easily, quickly and securely attaching the supporting member for an oscillatory eye setting to the wall of a doll head and which will positively insure a non-binding free oscillating motion of the eye members with respect to the openings 5 in the head wall without subsequent adjustment of either the supporting member, or of the eye setting. More particularly, my present improvements comprehend a novel form of the supporting member and 10 attaching means therefor which is essentially characterized by the provision of movable fastening or anchoring elements carried by the supporting member and adapted to be impaled in the structure of 15 the head wall, together with means on said supporting member adapted to be engaged with said elements and fixedly secure the same against any possibility of movement from their anchoring positions with respect 20 to the supporting member so that the latter is positively fixed against any possibility of displacement relative to the wall of the doll head, thereby insuring permanency in the relationship between the oscillatory eye 25 setting and the eye openings in the head wall.

It is another important object of my invention to provide a simply constructed and easily operated tool upon which the supporting member and the eye setting are adapted to be detachably mounted in a definite predetermined relation to each other, and said tool including a movable part adapted to impale the anchoring elements 30 in the wall of the doll head which is positioned over the tool with the eye members of the setting in engagement with the eye receiving cavities in the head wall, and said movable tool element also automatically engaging the securing means on the supporting member with said anchoring elements to securely lock the latter in their anchoring positions relative to the supporting member.

With the above and other objects in view,

the invention consists in the improved eye mounting and in the attaching tool therefor, as will be hereinafter more fully described, illustrated in the accompanying drawings, and subsequently incorporated in the subjoined claims.

In the drawings, wherein I have disclosed one simple and practical embodiment of my present improvements and in which similar reference characters designate corresponding parts throughout the several views,

Figure 1 is a vertical sectional view through the front wall of a doll head showing my improved eye mounting attached thereto;

Fig. 2 is a rear elevation of the head wall with the eye mounting applied, a part of the wall being shown in section;

Fig. 3 is a horizontal sectional view taken on the line 3—3 of Fig. 2;

Fig. 4 is a rear elevation of the mounting showing the relative position of the parts before attachment to the doll head;

Fig. 5 is a horizontal section taken on the line 5—5 of Fig. 4;

Fig. 6 is a side elevation of the tool, parts thereof being in section, and showing the supporting member and eye setting arranged thereon and the doll head positioned relative thereto prior to the attachment of the supporting member;

Fig. 7 is a plan view illustrating the essential parts of the attaching tool;

Fig. 8 is a transverse sectional view taken on the line 8—8 of Fig. 6;

Fig. 9 is a similar sectional view taken on the line 9—9 of Fig. 6, and

Fig. 10 is a detail side elevation partly in section of the movable tool member or anvil.

In the accompanying drawings, for purposes of illustration, I have shown the front portion of a doll head 5, the wall structure of said head being molded or otherwise fashioned from wood pulp, papier mâché or other composition material of similar nature. The front wall of the doll head is provided with the usual spaced eye openings, one of which is indicated at 7, arranged in appropriate symmetrical relation to the

other molded facial features of the head wall, the inner surface of said wall at each of the eye openings being milled out in the usual manner to provide a concave seating surface for the respective hemispherical eye members.

The improved eye mounting constituting one of the important features of this application, as herein shown embodies a supporting member for the oscillatory eye setting. This supporting member may be conveniently and inexpensively produced from a stamped sheet metal blank which is bent into channel-shaped form, providing the intermediate body wall 8 and the longitudinal side flanges 9 at opposite edges thereof. At a point intermediate of its ends the body wall 8 has a slot or opening 10 therein extending between the side flanges 9, and said flanges are each provided with a recess indicated at 11, in line with said slot for the reception of the cylindrical intermediate part 12 of the axis or shaft of the eye setting. The opposite end portions of this shaft at either side of the supporting member are preferably of rectangular form as indicated at 13 and upon the same the hemispherical eye members 14 are fitted and held thereby against independent rotative movement. To the center of the shaft or axis 12 the upper end of the usual pendulum rod 15 is suitably attached, said upper end of the rod having an angular rearwardly projecting terminal portion 16 adapted by contact with the body wall 8 of the supporting member to limit oscillatory movement of the eye members to their closed positions. To the other end of the rod 15 a suitable weight 17 is attached and by contact with the head wall limits the movement of the eye members to open position.

Each of the flanges 9 at the upper end edges thereof is provided with a recess indicated at 18, and the longitudinal edges of these flanges in spaced relation to their lower ends are each provided with a bayonet slot 18. These recesses and slots are adapted to receive suitably formed parts on a tool arm as will be later described in detail.

From the body wall 8 of the supporting member adjacent to its opposite ends a tongue 19 is struck to project inwardly between the side flanges 9 substantially at right angles to the body wall. Upon each of these inwardly projecting tongues, an anchoring member 20 is adapted to be engaged. As herein shown, each of these anchoring members consists of a resilient sheet metal plate normally of the bowed form illustrated in Figs. 8 and 9 of the drawings. This plate is centrally provided with a suitably formed opening 21 to receive the tongue 19 and the opposite ends of said plate have beveled edges indicated at 22 to thereby pro-

vide the tapering sharply pointed spurs 23. The side flanges 9 of the supporting member closely adjacent to the surface of the body wall 8 are provided at their opposite ends with the openings 24, and when the anchoring members are severally assembled with the supporting member upon the tongues 19 thereof, the points of the spurs 23 are engaged in said openings.

The wall of the doll head above the eye openings therein is internally formed with an enlargement or projection 25 and a similar internal enlargement or projection is also formed upon the head wall below the nose as indicated at 26. These enlarged wall sections are centrally provided with the vertical recesses 27 and 28 respectively which are adapted to receive the upper and lower ends of the supporting member as will be hereinafter described.

The supporting member with the eye setting mounted thereon is applied in operative relation to the doll head wall by means of a suitable tool. One embodiment of this tool is illustrated in the accompanying drawings. As shown, I provide a tool arm generally indicated at 29 extending laterally and upwardly at a slight inclination from the upper end of a standard 30 which is suitably fixed at its lower end to a bench supporting base. The arm 29 consists of parallel longitudinally extending side bars or rails 31 integrally connected at their ends by the transverse bar or cross piece 32. The rails 31 have correspondingly located upper edge portions 33 extending from the transverse connecting bar 32 in a horizontal plane and at the inner side of each rail an upstanding longitudinal rib 34 is formed upon these horizontal edge portions. Intermediate of the ends of the said edges 33, each rail 31 is provided with a vertical recess 35 and at one side of said recess each of the ribs 34 is formed with an upwardly projecting lug 36. At the opposite side of each recess 35 the rail 31 is formed with an upwardly projecting angular or hook shaped lug 37 and in line with these lugs, the cross bar 32 is provided at its opposite ends with the inwardly projecting lugs 38 spaced from the edges 33 of the rails 31.

Between the spaced rails 31 at their inner ends a lever 39 is fulcrumed intermediate of its ends upon the pin 40. The outer end portion of this lever is bifurcated, and the spaced arms 41 thereof have their end portions inwardly offset towards each other as indicated at 42 and provided with longitudinally elongated openings 43 therein. These openings are adapted to receive the ends of a shaft 44 upon which an anvil member 45 illustrated in detail in Fig. 10 of the drawings is suitably fixed intermediate of its ends. This anvil member has spaced side portions which straddle the ends of the

arms 41 of the lever 39, the upper edges thereof being provided with notches or recesses shown at 46. This anvil member at its opposite ends and in the upper surface thereof is centrally formed with a short longitudinal channel 47 which opens upon the end edge of said member. The wall of said channel at the inner end thereof is upwardly curved to provide a cam surface 48, the purpose of which will be presently explained.

In the attachment of my new eye mounting to the wall of the doll head, the eye setting is assembled with the supporting member with its shaft or axis seated in the recesses 11 thereof, and said supporting member is then arranged upon the tool arm, the pendulum rod 15 of the eye setting being positioned so that it will extend downwardly between the rails 31 and between the arms 41 of the lever 39 and rest upon the shaft 44. The flanges 9 of the supporting member are engaged upon the horizontal upper edges 33 of the rails and said member is slightly shifted longitudinally thereon so as to engage the lugs 37 and 38 on the rails 31 in the slots and notches 18 and 18' respectively of the flanges 9. It is of course, understood that the anchoring members or plates 20 are first assembled with the supporting member as shown in Figs. 8 and 9 before said member is thus attached to the tool arm. When the supporting member is arranged upon the rails 31, the lugs 36 on said rails engage the underside of the shaft or axis of the eye setting and lift the same slightly and support said axis above the inner ends of the recesses 11. The opposite ends of the anvil member 45 are engaged with the central portions of the respective anchoring plates 20 and the ends of the tongues 19 are opposed to the inner curved end walls 48 of the channels 47.

The doll head is now arranged over the tool arm and the hemispherical eye members 14 are engaged with the concave surfaces on the inner surface of the head wall at the respective eye openings 7. The head is adjusted with respect to the eye members until the pupils of said eye members are centrally positioned with respect to the lower edges of the eye openings as indicated in Fig. 8 of the drawings. In this position of the doll head, it will be noted that the opposite ends of the supporting member for the eye setting are located in the respective recesses 27 and 28 of the head wall. The angular position of the supporting member relative to the plane of the head wall is determined by the depth of the eye receiving cavities, and it will be observed that said supporting member is positioned at more or less of an inclination with respect to the general plane of the head wall so

that while said member at its upper end is substantially in contact with the head wall at the base of the recess 27 and is positioned wholly within said recess, the supporting member at its lower end is spaced 70 rearwardly from the base wall of the recess 28 and the flanges 9 of said member project rearwardly from the open side of the recess.

After the head has thus been properly adjusted with respect to the two eye members, the operator depresses the end of lever 39 projecting from the neck of the doll head. The anvil member 45 is thus raised vertically, the pin 44 moving upwardly in the recesses 35 of the tool arm, while the supporting member is held stationary upon the tool arm by the lugs 37 and 38. The ends of the anvil member bearing against the resilient anchoring plates 20, straighten or flatten the bowed plates, projecting the 85 spurs 23 on the ends thereof in opposite directions through the openings 24 in the flanges 9 and deeply impaling said spurs into the structure of the doll head. This straightening action by the anvil member 90 whereby the anchoring plates are thus impaled in the wall structure continues until all parts of said plates are substantially in a common plane as shown in Fig. 3 of the drawings. At the start of this movement 95 of the anchoring member, and shortly after the points of the spurs 23 have entered the structure of the head wall, the ends of the tongues 9 on the opposite ends of the supporting member are engaged by the cam surfaces 48 and said tongues are thereby bent in relatively opposite directions and extend through the channels 47 around the central part of the anchoring plate at one side of the opening 21 therein. Therefore, 100 when the anchoring plate is fully straightened out, said tongues will be bent into substantially U-shaped form and clinched upon the anchoring plates as shown in Fig. 1 of the drawings to prevent the return of said 105 plates to their normal bowed condition and the retraction of the spurs 23 from the wall structure. It will therefore, be apparent that these anchoring members are thus automatically fixed in a very positive and secure manner to the supporting member, while said supporting member is fixedly anchored at its opposite ends to the wall structure of the doll head by said anchoring plates.

After the supporting member for the eye setting has been attached to the wall of the doll head in the manner above explained, the head is shifted relative to the tool arm to disengage the lugs 37 and 38 from the slots and recesses in the flanges of the supporting member, whereupon the doll head with the supporting member and eye setting attached in operative relation to each other may be removed from the tool. It will be 130

evident that by the provision of my novel form of attaching means for the supporting member with the tool for engaging the attaching means with the doll head wall and subsequently locking the same in fixed relation to said wall and the supporting member, such oscillatory eye settings may be very easily, quickly and accurately mounted within the doll head so that the pupils of the eye members will oscillate in accurate relation to the respective eye openings. When the doll head with the mounting and eye setting attached is removed from the tool arm, the axis of the eye setting drops backwardly in the recesses 11 and seats against the closed ends thereof so that the peripheral surfaces of the respective eye members will not have a tight frictional bearing contact with the edges of the eye openings 7, thus permitting of the free and unretarded oscillatory motion of said eye members to their open and closed positions.

From the foregoing description considered in connection with the accompanying drawings, the construction of my improved eye mounting as well as the construction and manner of operation of the attaching tool therefor will be fully understood. It will be seen that after the mounting has once been attached, it is fixedly held against possibility of movement in any direction with respect to the wall of the doll head so that said supporting member cannot become accidentally displaced and release the eye setting from its proper operating position with relation to the eye openings or obstruct or retard the free oscillating motion of the eye setting. Also, it will be apparent that by reason of the construction of the eye mounting and the manner of its attachment with the eye setting in associated relation therewith to the wall of the doll head as above explained, no subsequent adjustments of the eye setting or the supporting member with relation to each other or with respect to the doll head wall is required in order to insure the proper operating motion of the eye members.

I have above described a form of the anchoring plates 20 and of the means for fixedly securing the same with relation to the supporting member, which has given excellent results in practice, nevertheless this part of my present disclosure as well as the particular form and construction of the channel shaped supporting member, may be susceptible of considerable mechanical variation in form and construction. Likewise the improved attaching tool as herein disclosed, while exceedingly simple and efficient for the purpose in view, might also be exemplified in numerous other alternative constructions. Accordingly, it is to be understood that I reserve the privilege of resorting to all such legitimate changes in the form, construction

and relative arrangement of the various elements as may be fairly embodied within the spirit and scope of the invention as claimed.

I claim:

1. An eye mounting for dolls comprising an eye supporting member adapted to be inserted within a doll head in position for attachment to the front wall thereof, resilient anchoring members carried by said supporting member and having parts impaling the structure of said wall when said resilient members are placed under tension, and movable means on the supporting member to coact with said anchoring members and rigidly fix the same in the latter position. 70

2. An eye mounting for dolls comprising an eye supporting member adapted to be inserted within a doll head in position for attachment to the front wall thereof, resilient anchoring members carried by said supporting member and having parts impaling the structure of said wall when said resilient members are placed under tension, and said supporting member having bendable parts adapted to be clinched upon the anchoring members to fixedly secure the same in the latter position with respect to the supporting member. 85

3. An eye mounting for dolls comprising an eye supporting member adapted to be inserted within a doll head in position for attachment to the front wall thereof, said member including spaced parts each having an opening therein, a resilient anchoring member having parts projecting through said openings and adapted to be subjected to pressure to place said anchoring member under tension and impale the said parts in the structure of the head wall, and means 100 for immovably locking the anchoring member in the latter position relative to said supporting member. 105

4. An eye mounting for dolls comprising an eye supporting member adapted to be inserted within a doll head in position for attachment to the front wall thereof, said member having side flanges each provided with an opening therein, a bowed resilient anchoring plate arranged between said flanges and having its opposite ends engaged in said openings, said plate adapted to be flattened out under pressure to thereby project the end portions thereof through said openings and impale the same in the structure of the head wall, and means for immovably locking the anchoring plate in the latter position with respect to said supporting member. 115

5. An eye mounting for dolls comprising an eye supporting member adapted to be inserted within a doll head in position for attachment to the front wall thereof, said member having side flanges each provided with an opening therein, a bowed resilient 125

- anchoring plate arranged between said flanges and having its opposite ends engaged in said openings, said plate adapted to be flattened out under pressure to there-
 5 by project the end portions thereof through said openings and impale the same in the structure of the head wall, and said supporting member having a bendable tongue struck from its intermediate portion adapted to be bent and clinched upon the anchoring plate to immovably lock the same in its anchoring position with respect to the supporting member.
 10 6. An eye mounting for dolls comprising a channel shaped eye supporting member adapted to be inserted within a doll head and vertically positioned with respect to the front wall for attachment thereto, the side flanges of said supporting member hav-
 15 ing openings therein adjacent their opposite ends, relatively movable anchoring means arranged in the channel of said supporting member and having parts movable outwardly through said openings and
 20 adapted to be impaled in the structure of the head wall, and additional means carried by the supporting member and adjustable relative thereto into locking engagement with said anchoring means to fixedly secure
 25 the same in anchoring position with respect to the head wall and the supporting member.
 30 7. An eye mounting for dolls comprising a channel shaped eye supporting member adapted to be inserted within a doll head and vertically positioned with respect to the front wall for attachment thereto, the side flanges of said supporting member hav-
 35 ing openings therein adjacent their opposite ends, relatively movable anchoring means arranged in the channel of said sup-
 40 porting member and having parts movable outwardly through said openings and adapt-
 45 ed to be impaled in the structure of the head wall, and said supporting member having bendable tongues struck from its interme-
 50 diate portion projecting into the channel thereof and adapted to be bent upon parts of said anchoring means to immovably lock the latter in anchoring position with respect to the head wall and the supporting member.
 8. In a mounting for oscillatory eye settings for dolls, a supporting member adapt-
 55 ed to be arranged between opposed internal-
 60 ly formed surfaces on the doll head wall, extending in predetermined angular relation to a common plane intersecting the centers of the eye openings in the head wall, anchoring means for said member consist-
 65 ing of a resilient normally bowed plate hav-
 70 ing end portions coating with spaced parts of said member and adapted to be engaged with the doll head structure by the applica-
 75 tion of pressure to said plate in a direction substantially at right angles to the front wall of the doll head whereby said plate is
 80 placed under tension and the supporting member secured in fixed relation to the head wall, and means for retaining said plate in anchoring position.
 85 9. In combination, a doll head having eye openings and opposed internal surfaces po-
 90 sitioned at substantially right angles to the front wall of the doll head, an oscillatory eye mounting comprising eye members and a connecting element therebetween, a sup-
 95 porting member engaged between said op-
 100 posed surfaces and having means support-
 105 ing said connecting element for oscillatory movement, a resilient anchoring element for said supporting member having parts co-
 110 operating with the supporting member and adapted to be moved in opposite directions by the application of a tensioning pressure to said element to position said parts in locked engagement with said opposed sur-
 115 faces of the head wall to thereby secure said member in fixed relation to said wall, and means for retaining said element in anchor-
 120 ing position.
 10. In combination with a doll head, means for mounting an oscillatory eye set-
 125 ting within said doll head, said means in-
 130 cluding a supporting member having bearing means to receive the axis of the eye setting, and anchoring means carried by said supporting member comprising a normally bowed resiliently yieldable part having wall impaling means adapted to be deformed under pressure to embed said means in the structure of the doll head wall, and additional means adjustable relative to said sup-
 135 porting member into engagement with said deformed anchoring part to immovably lock the latter in its anchoring position with respect to the supporting member.
11. In combination with a doll head, means for mounting an oscillatory eye set-
 140 ting within said doll head including a sup-
 145 porting member having bearing means for the axis of the eye setting, and means car-
 150 ried by said supporting member for rigidly securing said member to the front wall of the doll head, said means comprising an anchoring member having relatively mov-
 155 able wall impaling parts positioned through spaced openings in the supporting member and movable in opposite directions through said openings to impale said parts in the structure of the doll head wall, and said sup-
 160 porting member having an integrally formed part bendable relative thereto into engagement with said anchoring member to lock the wall impaling parts thereof against disengagement from the doll head wall.
- In testimony that I claim the foregoing as my invention, I have signed my name hereto.
- LEO J. GRUBMAN.
